UNITED STATES PATENT OFFICE.

GEORGE D. MUNISING, OF NEW YORK, N. Y.

BOTTLE CAPPER.

1,408,127.

Specification of Letters Patent. Patented Feb. 28, 1922.

Application filed January 12, 1921. Serial No. 436,703.

To all whom it may concern:

Be it known that I, GEORGE D. MUNISING, a citizen of the United States, residing at New York, in the county and State of New York, have invented certain new and useful Improvements in Bottle Cappers, of which the following is a full, clear, and exact specification.

This invention relates to bottle capping devices, and has for its object to provide a simple form of hand-operated appliance for this purpose which may be easily operated and will perform its work with certainty and precision.

One aim of the invention is to provide a bottle capper which may be supported on the wall at any convenient place and is provided with means for supporting the bottle by the neck while the cap is being placed thereon. Another object is to provide means for adjusting the capping device with respect to the neck holding device so as to accommodate bottles with different types of necks. Other objects will appear as the description proceeds.

The invention will be first hereinafter described in connection with the accompanying drawings, which constitute part of this specification, and then more specifically defined in the claims at the end of the description.

In the accompanying drawings, wherein similar reference characters are used to designate corresponding parts throughout the several views:—

Figure 1 is a side elevation of a bottle capping device constructed substantially in accordance with this invention, the same being attached to the wall.

Figure 2 is a front elevation of the capping device as shown in Figure 1.

Figure 3 is a vertical sectional view of the device taken from front to back through the center thereof, showing the neck of a bottle supported in position, and the depressed cap-fixing position of the plunger in dotted lines, and

Figure 4 is a horizontal section of the device taken just above the bottle neck gripping jaws.

Figures 3 and 4 are drawn to a somewhat larger scale than Figures 1 and 2.

Referring more particularly to the drawings, 1 and 2 are brackets adapted to be secured to the wall 4 by screws 3. Said brackets are adjustably connected one above

the other by bolts 5 extending upward from the lower bracket 1 and secured to the lugs 6 of the upper bracket 2 by nuts 7 whereby one bracket may be adjusted vertically with respect to the other to accommodate bottles with different styles of necks and which will therefore project different distances above the gripping jaws hereinafter described.

The bracket 1 has an opening 8 in its horizontal portion through which the mouth of a bottle 30 may be inserted, as indicated in Figure 3, and above said opening a pair of oppositely extending jaws 9 are pivoted or hinged to the bracket 1 at 10, said jaws having semi-circular notches 12 in their free ends to grip under the mouth of the bottle, as at 31, Figure 3, for supporting said bottle while it is being capped, and the jaws being hinged to the lugs 11 on the bracket 1 as shown in Figure 4. The jaws 9 have notches 50 through which the bolts 5 extend, as also shown in Figure 4, said notches being of such size as to permit said jaws to be swung upward far enough to allow the bottle neck to be inserted and removed when desired.

The upper bracket 2 has a pair of upstanding lugs 22 between which a hand lever 20 is pivoted by means of the cross pin 21. Also pivoted to said hand lever near to 85 but eccentrically of the pivot pin 21 a pair of depending links 17 are attached by a cross pin 19, the lower ends of said links being pivotally attached to a lug 16 on a plunger 14 having lateral wings 29 slidingly mounted on the bolts 5, as best shown in Figure 2. The construction is such that when the hand lever is moved to vertical position, as shown in solid lines in Figure 3, the plunger will be raised or moved upward 95 away from the bottle neck gripping jaws, while movement of the hand lever downwardly and forwardly to horizontal position, as shown in Figure 1, will cause the plunger to move down towards the said jaws.

A cavity 15, Figure 3, is formed in the under face of the plunger 14 to fit over a bottle cap, one of which is indicated at 33 in the same figure, the vertical peripheral walls 105 of said cavity serving to force the rim of the cap into engagement with the bead 32 of the mouth of the bottle neck 30 when said plunger is fully depressed. In order to insure the proper seating of the cap well down 110 upon the mouth of the bottle before the rim of said cap is contracted around the bead 32,

an auxiliary plunger 27 is mounted in the cavity 15 of the plunger 14, being movable with a vertical stem 24 which extends up through the plunger 14 and lug 16 thereon, 5 as best illustrated in Figure 3. A notch 28 is preferably formed in said stem 24 adapted to co-operate with the pivot pin 18, which connects the links 17 to said lug 16, for limiting the movement of said auxiliary plunger with respect to the main plunger 14. The upper end of the stem 24 is adapted to be engaged by a cam portion 23 on the pivoted end of the hand lever for forcing said auxiliary plunger downward to properly 15 seat the cap 33 on the bottle neck in the capping operation which will be clearly understood from the foregoing description.

It will be noted in Figure 3 that the stem 24 extends loosely through a passage 26 in 20 the plunger 14 and lug 16, and that the pivot pin 18, which connects the links 17 to said lug, is arranged partially in said passage, so as to co-operate with the notch 28 in the stem as previously explained. It will also 25 be observed that the bottle neck gripping notches 12 in the jaws 9 have beveled edges 13 to better grip the bottle neck below the mouth, as shown in Figure 3. In the operation of the device, after the bottle neck has 30 been engaged with the jaws 9, the lever 20 is moved on its pivot from vertical to horizontal position, thereby depressing the plunger 14 to crimp the flange of the cap 33 around the bead 32 at the mouth of the 35 bottle. As said plunger 14 is depressed by means of the links 17 connecting the same to the lever 20 eccentrically of the pivot 21 of said lever, the cam 23 of the lever engages the stem 24 and advances the auxiliary plunger 27 so as to hold the cap firmly in 40 place over the mouth of the bottle during the final descent of the plunger 14 for crimping the flange of said cap.

I claim:—

45. 1. In a bottle capper, the combination with a bracket having an opening therethrough,

of oppositely extending jaws for gripping a bottle neck to support the same, said jaws being hinged to swing upwardly and away from the bracket to release a bottle neck 50 and to fold down flat upon said bracket to engage a bottle neck, another bracket arranged above the first one, rods extending from one bracket to the other and arranged between the hinges of the bottle gripping 55 jaws, there being notches in said jaws to clear the rods, and a plunger mounted to slide on said rods for capping a bottle when supported by said jaws.

2. In a bottle capper, the combination 60 with a plunger having a cavity to fit over a cap for crimping the same upon a bottle, of means for reciprocating said plunger including a lever and links connected to said lever and plunger, an auxiliary plunger arranged in the cavity of the first plunger and having a stem extending up through the same, and a cam on said lever for engaging said stem and moving the auxiliary plunger into engagement with the cap in advance 70 of the main plunger and for holding said auxiliary plunger in contact with said cap for retaining the latter in place on the bottle, while the main plunger is advanced to crimp the cap on the bottle. 75

3. In a bottle capper, the combination with a plunger having a cavity to fit over a cap, of a lever connected to said plunger by links and a pivot pin extending through the plunger, an auxiliary plunger arranged 80 in the cavity of the first plunger for the purpose specified, a stem extending up through a passage in the first plunger for actuating the auxiliary plunger independently to a certain extent, said pivot pin 85 extending into said passage, and means on said stem to engage said pin for limiting the independent movement of said auxiliary plunger.

In testimony whereof I have signed my 90 name to this specification.

GEORGE D. MUNSING.
